CLAIM

I claim the ornamental design for a kettlebell, as shown and described.

DESCRIPTION

FIG. 1 shows a top isometric view of a kettlebell in accordance with the present design.

FIG. 2 shows a bottom isometric view of the kettlebell in FIG. 1.

FIG. 3 shows a front elevation view thereof.

FIG. 4 shows a rear elevation view thereof.

FIG. 5 shows a right side elevation view thereof.

FIG. 6 shows a left side elevation view thereof.

FIG. 7 shows a top plan view thereof; and,

FIG. 8 shows a bottom plan view thereof.

The even broken lines illustrate portions of the kettlebell that form no part of the claimed design. The dash-dot broken lines illustrate boundaries that form no part of the claimed design.

1 Claim, 8 Drawing Sheets
